UNITED STATES PATENT OFFICE.

WILLIAM C. SHANLEY, OF DES MOINES, IOWA.

SEWER TRAP.

1,403,875.

Specification of Letters Patent. Patented Jan. 17, 1922.

Application filed August 20, 1919. Serial No. 318,753.

To all whom it may concern:

Be it known that I, WILLIAM C. SHANLEY, a citizen of the United States, and a resident of Des Moines, in the county of Polk and State of Iowa, have invented a certain new and useful Sewer Trap, of which the following is a specification.

The object of my invention is to provide a sewer trap of simple, durable and inexpensive construction, and in which the cap or cover of the trap may be moved through an arc of a circle after the trap has been set, and without affecting the seal of the cap or cover on the trap body, and whereby a connecting pipe leading to the trap may be easily and conveniently applied at any part of said segment for the convenience of an operator in connecting a drain pipe to a trap.

20 My invention consists in the construction, arrangement and combination of the various parts of the device, whereby the objects contemplated are attained, as hereinafter more fully set forth, pointed out in my claim, and illustrated in the accompanying drawings, in which:

Figure 1 is a vertical, central, sectional view of my improved trap.

Figure 2 is a top or plan view of the trap. 30 Figure 3 shows an elevation illustrating the manner of attaching my improved trap to a bath tub.

Figure 4 is an enlarged, detail sectional view illustrating my improved gasket.

35 Figure 5 is a central, sectional view through my improved gasket; and

Figure 6 is a top or plan view of the parts shown in Figure 5.

Referring to the accompanying drawings, 40 I have used the reference numeral 10 to indicate generally a hollow, cylindrical trap body, which is open at its upper end and provided with internal threads 11 formed on a shoulder 12 to coact with a downwardly extending flange 13 of a cap or cover 14.

The cap or cover member 14 projects laterally beyond the downwardly extending flange 13 and a liquid tight joint is insured between the cap and the body by the use of 50 my improved gasket, which comprises a rubber ring 15, which rests on the upper edge of the body 10 and a metallic ring 16, having at its outer edge a downwardly extending flange 17.

55 From the construction of the parts just

described, it will be seen that the rubber ring 15 is enclosed between the upper edge of the body 10, the sides of the flanges 17 and 13 and the lower surface of the ring 16. When therefore the trap cover is screwed 60 down on to the body, pressure will be exerted against the surface of the ring 15 from all sides, thereby insuring a liquid tight joint.

In addition to this feature, it will be 65 noted that when the cover 14 is to be unscrewed, then the rubber washer 15 contacts with the flange 13 only at one edge, while the remaining pressure of the cover member against the body member is carried by the 70 metal to metal contact of the threads 12 and the ring 16.

Corrosion of the flange 13 or any other condition, which would cause an ordinary rubber ring to cling either to the body 75 member or to the cover member to prevent unscrewing the latter, is therefore limited to the surface exposed to one edge of the compressible washer, so that the cover may be very readily unscrewed, even though 80 it has been untouched for a long period of time.

Extending through the cover member 14 is an inlet pipe 18, which is preferably composed of non-corrosive metal, such for instance, as brass, and the inlet pipe is held in place by the threads 19, which coact with threads disposed within a shoulder or flange 20 mounted on the cover. The shoulder or flange 20 is a wrench lug and is disposed 90 eccentrically relative to the cover for purposes which will hereinafter be described.

Mounted above the wrench lug 20 is a lock washer 21. Slidably received within the inlet pipe 18 is a second pipe 22 preferably composed of brass or other non-corrosive material, which may be locked from movement relative to the pipe 18 by screwing down a collar 23 against a compressible washer 24. Suitable means may be provided for securing the pipe 22 to the waste 95 100 and overflow 26 of a bath tub 27.

It will be seen that when the parts are installed as shown in Figure 3, that then the body 10 may be set in the floor and the wrench lug 20 may be used to turn the cover member 14 to any position, so that the pipe 22 can register with the fittings of the tub. The dotted lines in Figure 2 clearly illustrate the various positions to which the pipe 110

22 or the pipe 18 may be moved in order to take care of faulty measurements, miscalculations, errors and other reasons for bending pipes, so that their ends may be connected together.

10 Adjacent to the bottom of the body 10 is a clean out plug 28, which is threaded to a collar 29 and a liquid tight joint formed by means of washers or gaskets 30 and 31 similar to the gaskets 15 and 16.

15 Extending laterally from one side of the body adjacent to the upper portion thereof is the waste or outlet pipe comprising a collar 32 into which is threaded a T 33, having one of its openings turned upwardly to receive a second clean out plug 34, which is sealed relative to the T in the same manner, as are the plug 28 and the cover member 14.

20 The plug 34 and the plug 28 are both provided with eccentric wrench lugs 35 similar to the lugs 20, whereby the plugs may be more readily loosened for unscrewing or tightening when being screwed.

25 An advantage of my improved construction resides in the fact that my improved trap may be installed either in a floor or in a pipe shaft or in fact in any place where traps are ordinarily used with a minimum amount of labor and without the necessity for "wiping in" lead joints.

30 It is also possible to rotate the cap 14 through approximately 180 degrees to thereby position the pipe 22 to register with any fitting to which it is to be connected. Whenever

35 it is desired to unscrew either the clean

out plugs or the cap 14, the eccentric wrench lugs render the operation comparatively easy.

Some changes may be made in the construction and arrangement of the parts of my improved device, without departing from the essential features and purposes of my invention, and it is my intention to cover by my claim any modified forms of structure or use of mechanical equivalents which may be reasonably included within its scope.

I claim as my invention:

In a device of the class described, the combination of a hollow body open at its upper end and having a discharge outlet at one side near the top, a screw cover for the body portion having a raised wrench lug arranged eccentrically relative to the cover, said wrench lug being internally screw threaded, an inlet pipe open at both ends and screwed into the said wrench lug and extended downwardly into the body to a point near the lower portion thereof, and a compressible gasket device between the cover and the body, said parts being so arranged that after the body has been fixed in position, the cover may be turned a part of a revolution without substantially affecting the gasket seal and whereby the wrench lug may be moved to position where it may be readily and easily aligned with and connected to a pipe to discharge into the body portion.

Des Moines, Iowa, August 4, 1919.

WILLIAM C. SHANLEY.
